UNITED STATES PATENT OFFICE.

WILLIAM J. HERDMAN, OF TORONTO, ONTARIO, CANADA.

APPARATUS FOR TRANSLATING ELECTRICAL ENERGY INTO SOUND WAVES.

Application filed January 9, 1924, Serial No. 685,147. Renewed March 2, 1925.

My invention relates to apparatus for translating electrical energy into sound waves, and pertains specifically to that class of such apparatus generally known as loud speaking telephone receivers.

The principal objects contemplated by my invention comprise producing a loud speaking receiver, which, while being of the simple electro-magnetic type, is capable of utilizing relatively large operating currents to produce sound waves of relatively great amplitude, that a large volume of sound may be produced, further, a loud speaker in which clarity of tone and absence of distortion and disagreeable overtones due to the natural period of the diaphragm is attained.

I accomplish these and other very desirable features which will hereinafter be pointed out and described by means of the novel device illustrated in the drawings and described in the accompanying specification.

In the drawings which accompany and form a part of this specification, and in which like reference numerals designate corresponding parts throughout:

Fig. 1 is a plan view of one embodiment of my device.

Fig. 2 is a partially sectioned elevation of the same, a quarter of which is full sectioned on the line AA of Fig. 1, and the remaining section of which is partially sectioned on the same line.

Fig. 3 is a sectional elevation of the same taken on the line BB of Fig. 1.

Fig. 4 is an enlarged sectioned detail of the annular ridge and annular groove.

Referring now to the figures, my device comprises a supporting base 10, preferably turned of wood in the shape shown in the figures. The central portion of the base is provided with a substantially hemispherical recess or aperture 11 designed to contain and partially house the operating elements of the loud speaker. A cover 12 is preferably formed of brass or other suitable material, and is adapted to be attached to the base 10 by means of screws 13 as shown. The cover 12 serves to support and also to, in conjunction with the base, completely house the operating portions of the loud speaker. These operating elements comprise an upper diaphragm clamp 14, preferably composed of brass and provided with a centrally disposed integral socket adapted

to receive and support a horn or other acoustic amplifying outlet 16. The socket is provided with a central aperture of substantially equal internal diameter to the internal diameter of the stem of the horn 16. The clamp 14 is further provided with four threaded bosses 17, which permit of the operating elements being attached to the cover 12 by means of screws 18, and is provided with an annular sound chamber 19 of smaller internal diameter than a diaphragm 20, which is adapted to be clamped between the upper diaphragm clamp 14 and a lower diaphragm clamp 21. The lower diaphragm clamp 21, preferably constructed of brass, is provided with a centrally disposed sound chamber 22, which is of smaller diameter than the diaphragm 20, and the clamp is further provided with an internally threaded aperture adapted to receive an externally threaded cup 23, likewise composed of brass or other non-magnetic material. The upper diaphragm clamp 14 and the lower diaphragm clamp 21 are adapted to be maintained superposed one on the other by means of screws 25, and dowels 24, as shown in Figs. 2 and 3. The screws 25 and dowels 24 are disposed with relation to each other as indicated in Fig. 1. The upper diaphragm clamp is provided with an annular ridge 26 which is concentric with the recessed sound chamber and disposed near the edge thereof and is adapted to substantially register with an annular groove 27, provided in the lower diaphragm clamp 21, and likewise concentric with the sound chamber 22. The diaphragm 20 is adapted to be positioned on the lower clamp member 21 by means of the dowels 24, which likewise serve to position the upper diaphragm clamp 14. As the screws 25 are seated, the diaphragm is tensioned due to the action of the annular ridge in forcing the diaphragm to conform to the contour of the annular groove, and as shown by the center lines in Fig. 4, the annular ridge is slightly smaller in mean diameter than the annular groove, so that the central portion of the diaphragm will be stretched or tensioned, the degree of tensioning depending upon the diameter, thickness and material used, to give the diaphragm a natural period of about that of the medium tones of the human voice.

The cup 23 is provided with insulated

binding posts 28 and 29, to which are attached the terminals of a pair of operating magnets 30 and 31. These operating magnets are each provided, as shown in Fig. 2, 5 with an annealed soft iron core 32, bent at substantially right angles that they may be seated on extension pole pieces 33 and 34 respectively, to which the permanent magnet 35 is attached by means of screws 36 and 10 37. The permanent magnet is composed of tungsten magnet steel, and is, of course, hardened.

It will be noticed that the cup 23 is provided, as shown in Fig. 1, with milled flats 15 40 and 41, to produce apertures through which the extension pole pieces 33 and 34 enter the cup to provide a continuous magnetic junction through the pole pieces 32 with the permanent magnet 35. The cup 23 20 is further provided with a lever 42 to which is attached a handle 45, the lever being secured to the bottom surface of the cup 23 by means of screws 43 and 44. As the cup 23 is threaded into the internally threaded 25 opening provided therefor in the lower diaphragm clamp 21, it is obvious that as the lever 42 is rotated, the cup will be moved forward or back in this opening, to position the pole pieces as 32 with respect to their 30 distance from the diaphragm 20. By this means the tone produced may be changed in quality, and the pole pieces may be adjusted to produce optimum quality. Also the distances of the pole pieces from the 35 diaphragm may be increased to permit the diaphragm to vibrate through relatively large amplitudes without impinging upon the pole pieces and thus permit relatively large amounts of energy to be utilized to 40 produce relatively large sound volumes, without occasioning distortion due to contact between the diaphragm and the pole pieces. It will be obvious that the cup 23 must thread into the threaded opening provided therefor accurately, to eliminate the 45 possibility of undesired relative motion between the cup and the lower diaphragm member. To this end, the diaphragm clamp is provided with oppositely located slots 46 and 47 which, with the screws 49 and 48, serve as a means for compressing a thread on the clamp 21 to compensate for deficiencies in manufacture or wear. This is a very 50 important feature, as any undesired relative motion existing between the clamp 21 and the cup 23 will obviously reduce the efficiency of the device.

It will be noted in Fig. 1 that a portion 55 of the wooden base near the upper edge thereof, is cut away to provide an opening 50 to permit of movement of the lever 42. It will be further noticed that an opening 60 is provided in the base to permit contact, by means of a flexible cord or other 65 conductor, with the binding posts 28 and 29.

In carrying out my invention, I employ a diaphragm of approximately 4" diameter, the free vibrating portion of which is approximately 3 1/4" diameter. I find that a diaphragm of annealed iron of the above 70 noted dimensions, and of about .010 of an inch in thickness, gives remarkably good results, when the diaphragm is tensioned as heretofore mentioned to have a natural period of about 500 cycles per second. 75

While I have thus described one embodiment of my device, it is to be distinctly understood that I may vary the details thereof without departing from the spirit or narrowing the scope of my invention. 80

Having thus completely described my invention, what I claim as new and desire to secure by United States Letters Patent is as follows:—

1. In a loud speaking receiver, an upper 85 clamp provided with an acoustic outlet, a lower clamp, an aperture therein, a diaphragm adapted to be positioned by dowels, and maintained between said upper and lower clamps, a cup adapted to be adjustably maintained in the aperture in said lower clamp, a pair of operating electro-magnets maintained within said cup, a pair of extension pole pieces emerging through 90 apertures provided in said cup, a permanent magnet adapted to be attached to said extension pole pieces, and means whereby said operating magnets carried by said cup may be moved with relation to said diaphragm. 95

2. In a loud speaking receiver, an upper 100 clamp provided with an acoustic opening, a sound chamber and an annular ridge concentric with said sound chamber and disposed near the edge thereof; a lower clamp provided with a series of dowels near the outer edge thereof, and further provided with a threaded centrally disposed aperture, a sound chamber and an annular groove disposed concentric with said sound chamber; a diaphragm adapted to be positioned by 105 the dowels in said lower clamp and to be tensioned by the action of said annular tongue and groove when said upper and lower clamps are in normal position; a threaded cup adapted to be maintained in the centrally located aperture in said lower clamp, a pair of operating electro-magnets maintained centrally within said cup, and adapted to be positioned thereby in relative 110 close proximity to the central portion of said diaphragm, and a lever attached to said cup whereby said cup may be moved within the opening provided therefor in said lower clamp, to vary the distance between said operating electro-magnets and said diaphragm. 115

3. In a loud speaking receiver, an upper diaphragm clamp provided with a centrally disposed acoustic opening, a sound chamber disposed concentric with said acoustic opening, and an annular ridge disposed near the edge 120

- of said sound chamber and concentric therewith; a lower diaphragm clamp provided with a centrally disposed threaded aperture, a sound chamber and an annular groove disposed near the edge of said sound chamber and concentric therewith; a diaphragm adapted to be maintained between said upper and lower clamps, and to be formed near the edge thereof by the action of said annular ridge and groove to have its central portion tensioned; an externally threaded cup adapted to be maintained within the threaded aperture in said lower diaphragm clamp; a pair of operating electro-magnets maintained centrally within said cup; extension pole pieces for said magnet emerging through apertures provided therefor in said cup; a permanent magnet maintained without said cup and attached to said extension pole pieces; and a lever provided with a handle and attached to the bottom surface of said cup whereby said cup may be moved relatively with respect to said lower diaphragm clamp to vary the distance between said electro-magnets and said diaphragm. 25
5. In a loud speaking receiver, an upper clamp provided with an acoustic outlet, a lower clamp provided with an aperture therein, a diaphragm adapted to be maintained between said upper and lower clamps, 30 means provided in each of said clamps and adapted to co-act by the act of clamping said diaphragm between said clamps to tension said diaphragm, a cup adjustably maintained in the aperture in said lower clamp, 35 a pair of operating electro-magnets maintained within said cup, a pair of extension pole pieces emerging through apertures provided in said cup and a permanent magnet adapted to be attached to said extension pole 40 pieces.

WILLIAM J. HERDMAN.
